INVENTOR

Edward H. Kruse,

BY

A. G. Burns ATTORNEY

UNITED STATES PATENT OFFICE.

EDWARD H. KRUSE, OF FORT WAYNE, INDIANA.

SWITCH-BOX BRACKET.

Application filed October 15, 1923. Serial No. 668,522.

To all whom it may concern:

Be it known that I, EDWARD H. KRUSE, citizen of the United States of America, and resident of Fort Wayne, in the county 5 of Allen and State of Indiana, have invented certain new and useful Improvements in Switch-Box Brackets, of which the following is a specification.

This invention relates to improvements in 10 switch-box brackets, and the object thereof is to provide a readily attachable and adjustable bracket for switch boxes by means of which the switch boxes are secured permanently in the walls of buildings, it being 15 the especial purpose to construct the bracket and the switch box so as to admit of the attachment of the bracket to the box and of its adjustment thereon without resorting to the use of tools, and so that the bracket will 20 be held in proper alignment thereon when secured in place.

These objects are accomplished by the construction illustrated in the accompanying drawings, in which:—

Fig. 1 is a side elevation of a switch box including brackets thereon embodying the invention;

Fig. 2 is a plan view projected from Fig. 1; and

Fig. 3 is a fragmentary front elevation of the same.

The characters appearing in the description refer to parts shown in the drawings and designated thereon by corresponding characters.

The switch box 1 is of that general type used for permanent installation in walls of buildings for containing electrical switches, etc. In this instance, however, the top and 40 bottom walls 2 of the box each have an outset portion 3 that extends centrally from a point near the back of the box to a point near the front thereof, the portion 3 being formed of the metal sheet of which the box 45 is made. Each portion 3 has formed therein a transversely disposed pocket 4 that projects outwardly from the general plane of said portion so as to receive a corresponding pin 5 therein.

Upon the top and bottom of the box is secured a bracket 6 having parallel base members 7 that are spaced apart and connected at their rear ends by a transverse strap 8 that is arched sufficiently to clear 55 the outset portion 3 of the box when said

base portions are placed astride thereof and bear against the top or bottom of the box. Along the outer edge of each base portion 7 is formed an escalloped ridge 9 engageable by the corresponding projecting ends of the 60 pin 5, and thereby the bracket is fixedly held in place in connection with the box.

In utilizing the invention, the brackets are placed astride of the outset portions and are moved lengthwise thereon to the desired 65 position where they are held by inserting the pins 5 through the corresponding pocket 4 so that the projecting ends thereof bear against the ridges of the bracket.

By this construction the brackets may be 70 readily applied to the box and adjusted thereon, and readjusted as occasion may arise when installing the box without the use of screws and tools as in the ordinary practice. When the brackets are secured on 75 the box by the pins, their forward movement is limited by their arched straps 8, while their backward movement is limited by their forward ends which are stopped by contact with said pins. 80

What I claim is:—

1. In combination, a switch box having in its top and bottom an outset portion centrally disposed and extending from a point near the back of the box to a point near the 85 front thereof, each portion having a transversely disposed pocket formed therein; a bracket for the top and bottom, each bracket having parallel base members spaced apart and an arched connection at their rear ends, 90 there being along the outer edge of each base portion an escalloped ridge; and a removable pin extending through each pocket, its ends having engagement with the ridges of the corresponding bracket and holding 95 the base of the bracket astride of the corresponding outset portion.

2. In combination, a switch box having in its top and bottom a corresponding outset portion longitudinally disposed between 100 its front and back and formed with a transverse pocket; a bracket on the top and bottom of the box, the base of each bracket having guided relation with the corresponding outset portion; and a pin extending through 105 each of said pockets and engaging the base of the corresponding bracket so that said bracket is thereby held adjustably in position.

3. In combination, a switch box having at 110

its top and bottom a corresponding outset portion formed with a pocket; a bracket for the top and bottom of the box, each bracket being positioned with its base astride of the corresponding outset portion, there being scalloped ridges on the base of said bracket; and a pin extending through each of said pockets and engaging said ridges to hold the

corresponding bracket adjustably in connection with the box.

In testimony whereof I affix my signature in presence of two witnesses.

EDWARD H. KRUSE.
